UNITED STATES PATENT OFFICE.

WALLACE W. STAUFFER, OF AKRON, INDIANA.

DOUGH CUTTER.

Application filed June 4, 1925. Serial No. 34,930.

This invention relates to the cake, biscuit and doughnut cutter forming the subject matter of my U. S. Letters Patent, No. 1,486,810 granted March 11, 1924, and comprising an outer cutter, an inner cutter, and means by which the inner cutter may be secured in different positions with respect to the outer cutter.

The invention has for one of its objects to improve the general construction of the inner cutter securing means to the end that the inner cutter will be secured in the required adjusted position against casual displacement during the use of the device.

With the above and other objects in view, the invention consists of the construction, combination and arrangement of parts hereinafter fully described and claimed, and illustrated in the accompanying drawing, wherein:

Figure 1 is a view in side elevation of the cutter equipped with the improved securing means,

Figure 2 is a sectional view taken on the vertical plane indicated by the line 2—2 of Figure 1,

Figure 3 is a view similar to Figure 1 illustrating a slightly modified form of the securing means, and

Figure 4 is a sectional view taken on the vertical plane indicated by the line 4—4 of Figure 3.

Corresponding and like parts are referred to in the following description, and designated in the several views of the drawing, by similar reference characters.

In the drawing, 1 designates the outer cutter, 2 the adjustable inner cutter, and 3 the handle to which the inner cutter is secured. The outer cutter 1 is of shallow cylindrical formation, and is fully open at its lower and closed at its upper end. The upper end wall 4 of the outer cutter 1 is provided with a plurality of openings 5 through which the air escapes during the use of the device. A sleeve 6 in which the inner cutter 2 and handle 3 are slidably mounted, extends upwardly from the wall 4 and is provided in a side thereof with a plurality of vertically aligned openings 7, 8 and 9. The inner cutter 2 is of tubular formation, and the lower end of the handle 3 is secured to and within this cutter by a latch pin 10 which is also adapted to secure the cutter in any of its various adjusted positions with respect to the outer cutter 1.

When the latch pin 10 is in the opening 7, the inner cutter 2 projects below the outer cutter 1, when in the opening 8 the lower end of the inner cutter is approximately in alinement with the lower end of the outer cutter, and when in the opening 9 the lower end of the inner cutter is approximately in alinement with the under side of the wall 4. It will thus be seen that the device may be used to cut small biscuits or cakes, doughnuts, and large biscuits or cakes.

The latch pin 10 passes through an opening 11 in the inner cutter 2 and has its inner end secured to the upper or free end 70 of a leaf spring 12 which is positioned within a recess 13 in a wall of the handle 3. The recess 13 is located in that portion of the handle 3 situated within the inner cutter 2, and is provided with an upwardly and 75 outwardly extending wall 14. The lower end of the spring 12 is secured to the wall 14 by means of an element 15 which may take the form of a staple, screw or the like. Due to the inclination of the wall 14, the spring 80 12 is held against the inner side of the inner cutter 2 under tension, with the result that the latch pin 10 is yieldingly supported in projected position. When it is desired to adjust the inner cutter 2 with respect to the 85 outer cutter 1, it is only necessary to press back the latch pin 10 beyond the inner surface of the sleeve 6 and at the same time apply pressure to the handle 3 in the direction in which it is desired to move the inner 90 cutter.

In the structure shown in Figures 3 and 4, the latch pin 10^a is secured to a spring 12^a fastened to the outer cutter 1^a, and the openings 7^a, 8^a and 9^a are formed in a side of 95 the inner cutter 2^a. The spring 12^a is secured to the end wall 4^a of the outer cutter 1^a by a rivet 16, and the latch pin 10^a passes through a notch 17 in the upper end of the sleeve 6^a which, due to the securing of the latch pin to the outer cutter 1^a and to the formation of the openings in the inner cutter 2^a, can and is made considerably shorter than the sleeve 6. When it is desired to retract the latch pin 10^a so as to permit the 100 inner cutter 2 to be adjusted with respect to the outer cutter 1^a, it is only necessary to exert an outward pull upon the upper end of the spring 12^a. The handle of this device is designated 3^a and the openings in the wall 110 4^a are designated 5^a.

From the foregoing description, taken in

- connection with the accompanying drawing, it should be apparent that the means here employed will hold the inner cutter against casual displacement during the use of the device, permit the inner cutter to be readily adjusted with respect to the outer cutter, and secure the parts together promptly upon the movement of the inner cutter into the desired adjusted position.
10. It should be understood that the drawing is merely illustrative and does not pretend to give exact proportions. Furthermore, the said drawing is illustrative of a preferred construction, it being my expectation that various changes and modifications may be made without departing from the spirit and scope of the invention.
- What is claimed is:—
1. A device of the character set forth, comprising an outer cutter, a sleeve carried by said cutter and provided with spaced openings, an inner cutter slidable in said sleeve, a handle secured to said inner cutter and provided with a recess having an inclined wall, a leaf spring secured at one end to said

wall, and a latch pin carried by the free end of the spring for passage through one of said openings to secure the inner cutter in the required adjusted position.

2. A device of the character set forth, comprising an outer cutter, an inner cutter adjustable with respect to the outer cutter, a handle, and yielding means carried by the handle and engaging the inner cutter to connect these parts together and adapted to engage the outer cutter to secure the inner cutter in the required adjusted position.

3. A device of the character set forth, comprising an outer cutter, an inner cutter adjustable with respect to the outer cutter, a handle, and yielding means engaging the inner cutter and handle and secured to one of these parts, said yielding means serving to connect the inner cutter and handle together and adapted to engage the outer cutter to secure the inner cutter in the required adjusted position.

In testimony whereof I affix my signature.

WALLACE W. STAUFFER.
